[57] CLAIM

The ornamental design for a carrying attachment for a bottle,
as shown and described.

DESCRIPTION

FIG. 1 is a front elevational side view of a carrying attachment for a bottle showing my new design.

FIG. 2 is a right side elevational view thereof;

FIG. 3 is a top plan view thereof;

FIG. 4 is a bottom plan view thereof;

FIG. 5 is a left side elevational view thereof;

FIG. 6 is a rear elevational view thereof;

FIG. 7 is a perspective view thereof showing my new
design;

FIG. 8 is another perspective view thereof; from the bottom
plan view; and,

FIG. 9 is another perspective view on a reduced scale with
a bottle and carrying strap shown in broken lines for
illustrative purposes only and forming no part of the claimed
design.
